ROLLER BELT CONVEYOR FOR MOUTHPIECE CIGARETTE ASSEMBLIES

George Dearsley, Raleigh, N.C., and Tennes I. Erstad, Brooklyn, N.Y., assignors to American Machine & Foundry Company, a corporation of New Jersey

Filed July 14, 1958, Ser. No. 748,444

10 Claims. (Cl. 198—183)

This invention relates to a cigarette making machine and more particularly to an apparatus and method for conveying assemblies of mouthpiece cigarettes by an endless roller belt conveyor.

Heretofore, it has been the practice, in assembly type mouthpiece cigarette machines, to support an assembly consisting of two single lengths of cigarette rod and a double mouthpiece length positioned therebetween on a series of supporting rollers carried on a drum or on rollers supported on a sprocket chain. When the supporting rollers are carried on a drum, certain operational difficulties arise due to the fact that for economy of space, the various mechanisms operating on the cigarettes must be grouped around the drum, which entails placing some mechanisms on the underside thereof, thus rendering them relatively inaccessible if the uppermost mechanisms are placed at a convenient working height.

To overcome these disadvantages sprocket chains carrying assembly supporting rollers were used. This turned out to be unsatisfactory because the various elements got out of timing due to wear in the joints of the chain, which resulted in a change in pitch of the rollers. This caused the uniting band to be applied too early or too late to the assembly.

It is therefore an object of this invention to provide a mouthpiece cigarette assembly conveyor which will not get out of timing through use and which will enable the components of the mouthpiece machine to be readily accessible.

A further object of this invention is to provide an endless flexible belt of cigarette support rollers which requires no lubrication.

Another object of this invention is to provide a flexible and non-extensible endless belt to support rollers which carry mouthpiece cigarette assemblies which will not change the pitch of the rollers because of wear.

A further object of this invention is to provide an improved roller conveyor belt which will be of simple construction and still adequately support cigarette assemblies.

Another object of this invention is to provide an endless conveying belt with its top run at a substantially horizontal plane making it possible to group all of the various operating mechanisms along the top run of the roller belt.

A further object is to provide a roller conveyor belt wherein assemblies will be entirely supported by adjoining rollers.

Another object is to permit the use of large sized rollers and not be limited to a small size roller and expensive bearings.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

2

Figure 1 shows a line diagram of such a belt running over two sets of sprockets.

Figure 2 shows a partial section on line 2—2 of Figure 1.

5 Figure 3 shows a partial section on line 3—3 of Figure 2.

Figure 4 shows an embodiment of our invention using a V belt.

Figure 5 is a section on line 5—5 of Figure 4.

10 As mentioned above, a horizontal arrangement of the uniting band applying operations is desirable because it enables all of the components to be positioned at a convenient working height so that they will be readily accessible. Our invention which we will now describe employs a roller belt assembly conveyor apparatus which will embody the advantages mentioned and which avoids the disadvantages heretofore encountered in roller belt assemblies conveyors.

15 Figure 1 shows a general configuration of a belt used in our improved mouthpiece cigarette assembly conveyor. Here the top run 10 of the belt 12 is supported on suitable guide rails to ensure that it runs in a horizontal plane. The various units of the machine are grouped about this horizontal plane. In this particular case, a pair of axially spaced sprockets 16 form the idle sprockets while axially spaced sprockets 14 are the drive sprockets. Both of these sets of sprockets 14 and 16 are on fixed centers and guide rails maintain the horizontal run 10 of the belt 12 horizontal while any slack will show up in the return run 18, the combined weight of the belt and rollers together with their fastening means producing sufficient tension to keep the belt taut at the horizontal top run.

20 Figure 2 shows a partial section 2—2 of the driving sprocket 14. The roller assembly is symmetrical about the vertical center line so that Figure 2 represents one end of the roller assembly mounted on one sprocket as seen when looking from the right and also the other end of the same roller as mounted on the other sprocket 25 of the same pair, as seen when looking from the left.

25 The roller belt assembly is carried on a hub 20, which is mounted on a suitable driving shaft (not shown). This hub 20 carries spaced sprockets 22, together with a pair of guide rings 24.

30 A belt 26 is trained over the sprockets 22 in the manner shown in Figures 1—3 and may be of the type known as a "Gilmer" rubber like material "timing belt."

35 Such a belt 26 consists of a flat endless band of a rubber-like material which is reinforced with steel cords 50 and which is provided with a series of toothlike projections 28 on one side, which projections 28 engage in corresponding grooves 30 in the sprockets 22 to provide the necessary location to ensure that the parts move in synchrony at all times.

40 55 In conventional applications of such a belt, the sprockets are provided with grooves which engage with every tooth on the belt in succession. In order to adapt this type of belt 26 for the purpose of our invention, special sprockets 22 are provided with grooves 30 to engage every alternate tooth 28 of the belt 26. A clearance groove 34 is provided between each alternate tooth groove 30 on the sprocket 22 in order to accommodate the fittings which carry the roller assembly. These fittings are located on the alternate teeth of the belt which 55 are not used for driving the belt 26.

60 70 Figure 3 is a partial section view taken on line 3—3 of Figure 2 and shows the belt 26 with its tooth 28 engaged with the corresponding groove 30 of the sprocket 22, the clearance groove 34, the carrier 36 for the roller 38 (shown in Figure 2) and clamp 40 which completes the roller supporting assembly mounted on the belt.

75 As shown in Figure 2, this assembly is held together

with the two screws 42 and 44 which hold the clamp 40 onto the carrier 36 by holding the intermediate surfaces 46 and 48 in close contact with each other. The proportions of these parts are such that the V-groove 35, formed in the carrier 36, Figure 3, fits closely around the tooth 29 molded on the belt 26, and is held in close contact therewith by means of the clamp 40 which, although tightened up tightly on the surfaces 46 and 48, is correctly proportioned to hold the carriage 36 in close contact with the tooth 29 of the belt 26 and yet will not permit undue compressive stress on the belt itself.

The roller 38 is fastened to the carrier 36 by means of the nuts 49 on each end of the central rod 50, which by means of the spacers 52 and 54 locates the ball races 58 and the ball races 56 which in turn carry the supporting rollers 38. The function of the ball races 58 is to act as a support for the assembly rollers 38 as it runs over the rail 62 thus causing the top run of the belt to run in a horizontal plane, or in any other desired configuration.

In order to axially adjust the assembly rollers and to provide an efficient guide for the traveling belt the clamp plates 40 are provided with clearance holes for the screws 42 and 44. These holes enable the clamps 40 to be positioned as required in an axial direction relative to the carriers 36. Thus, when assembling these parts, the clamps 40 are moved into close contact with the end guides 24 before tightening the screws 42 and 44 thus avoiding any undue clearance in this direction irrespective of any manufacturing errors which might exist on the parts. It will be understood that a belt constructed as described consists of an endless series of rollers positioned by alternate teeth on the belt, the intermediate teeth being used to drive the belt.

In such a system the pitch of the rollers and their diameters are chosen so as to adequately support the cigarette and filter assemblies during the operation of rolling on the uniting band, wherein we have shown how clamps may be secured to a flexible non-extensible belt. This belt may be of any suitable material, which does not have any links or pivot connection as for example a flat or V-belt with embedded wires running along its length to prevent the belt from stretching; or it may be an endless spring steel belt or it may be formed of spring steel leaves clamped together by the roller carrying fitting.

Figure 4 shows another embodiment of the invention.

In this case, the roller assembly is clamped onto the belt by means of carriers 66 and clamp plates 68 which are arranged as before by correctly proportioning the parts to obtain a solid abutment between the clamp 68 and the carriages 66 and at the same time to sufficiently compress the belt between them to maintain the position without unduly stressing the belt under compression. In this case, the assemblies are spaced on the V-belt solely by this frictional grip.

The belt is carried around V-pulleys 70 which fit the sides of the belt in a conventional manner. In addition, the pulleys 70 are also provided with grooves 71 to engage a suitable portion of the carriage 66 which also functions as a driving element in order to keep the rollers in time with the remainder of the machine. Figure 5 shows a section of the assembly on line 5-5 of Figure 4. Here carriage 66 and the clamp plate 68 are clamped onto the V-belt 72. As will be seen, the carriage 66 engages grooves 71 cut across the pulleys 70 and thereby keeps the whole assembly in timed relationship with the remainder of the mouthpiece cigarette making machine.

The assembly supporting rollers 74 are attached to this carrier 66 together with their guide rollers in a manner exactly as described in relation to Figure 2.

From the foregoing description it will be evident that in both embodiments of our invention, we have provided an improved horizontal cigarette mouthpiece assembly conveyor and support along which the assembly uniting operation can be performed in a horizontal plane, and because the carrying belts are flexible and not articulated as hitherto, require no lubrication.

The rollers are mounted in such an arrangement that their relative pitch will not be changed because of wear. Consequently, the critical timing involved in placing the tip end of a uniting band against the assembly, preliminary to rolling it thereabout, will always function as desired. Furthermore, there will be no tendency for cigarette assemblies to fall or be squeezed downwardly between adjoining rollers because they are supported in such a way that their relative spacing or pitch does not become changed over a period of time.

The invention hereinabove described may be varied in construction within the scope of the claims, for the particular device selected to illustrate the invention is but one of many possible embodiments of the same. The invention, therefore, is not to be restricted to the precise details of the structure as shown and described.

What is claimed is:

1. A cigarette assembly conveying and supporting apparatus comprising a pair of belts, tooth-like bulges of rubber-like material projecting from said belts, carriers shaped to fit on a number of said teeth, externally applied clamps to fasten said carriers on to said teeth and roller assemblies on which assemblies of cigarettes are supported by adjoining rollers.

2. A cigarette assembly conveying and supporting apparatus comprising a pair of flat endless bands of rubber-like material having a substantially horizontal top run, teeth-like projections attached on the other side of said bands, fittings shaped for engaging alternate teeth at the other side of said bands, rollers mounted and rotatable on said fittings and a source of cigarette assemblies being conveyed on said rollers.

3. An endless timing roller belt device for a cigarette machine comprising shafts, rollers rotatably mounted on said shafts, carriers having V-grooves supporting said shafts, clamps oppositely spaced from said carrier, tooth belts having alternate teeth fitted within said grooves and held on said carriers by said clamps, two pairs of sprockets having alternate large and small tooth-shaped grooves for the carrier to freely fit within the large grooves and teeth of the belts to be driven by the small corresponding grooves to ensure that the rollers move in synchrony with the remainder of the machine.

4. A conveying apparatus for a cigarette machine comprising a drive shaft, a hub mounted and driven by said drive shaft, a pair of sprockets having alternate large and small sized grooves mounted on said hub, two endless members having no pivoted components forming belts, a carrier fitting riding within said large grooves, clamps oppositely spaced from said carrier fittings for securing said carriers to the compression sides of said belts, and roller assemblies mounted on said carriers over which cigarette assemblies are supported in the mouthpiece cigarette making machine, a second pair of similarly grooved sprockets mounted on a second hub supported on a shaft on which the assembly may turn to support the opposite end of the endless members.

5. An endless timing apparatus for a cigarette machine comprising a pair of flexible non-extensible belts with rubber-like teeth, spaced sprockets with grooves in which some teeth of said belts engage, and over which said belts travel, clamps spaced and exteriorly attached to each of said belts, means for driving one pair of said sprockets for driving said belts, fittings integrally formed on the underside of said clamps to engage with corresponding grooves formed in said sprockets, and roller assemblies bridged between two transversely opposed fittings to support and convey cigarette assemblies in timed relationship with the other parts of the cigarette machine.

6. An assembly conveyor for a mouthpiece cigarette making machine comprising a pair of spaced flexible non-extensible endless bands, a series of block-like members mounted at equally spaced distances on each of said bands on the compression side thereof, shafts mounted transversely to said bands and bridged across each oppo-

site pair of said block-like members, and drive sprockets supported on the cigarette machine having recesses in which the block-like members mesh and are engaged to drive said bands in synchrony with the cigarette machine, a second pair of similarly grooved sprockets mounted on a second hub supported on a shaft on which the assembly may turn to support the opposite end of the endless bands.

7. A roller belt assembly conveyor for a mouthpiece cigarette making machine comprising endless bands, carriers mounted at equally spaced distances on said bands, extensions formed on said carriers, drive sprockets having grooves to mesh with the corresponding extensions of said carriers and to engage said carriers for advancement in timed relationship with the cigarette machine and supporting rollers supported by said carriers to convey cigarettes in mouthpiece cigarette making machine, a second pair of similarly grooved sprockets mounted on a second hub supported on a shaft on which the assembly may turn to support the opposite end of the endless members.

8. An assembly conveyor for a mouthpiece cigarette making machine comprising, a pair of spaced endless belts having no articulated links therein, pairs of spaced sprockets over which said belts are trained, spaced opposed clamps secured to said belts and supporting rollers at opposite ends between pairs of said clamps, said clamps being positioned sufficiently close to each other so as to enable said rollers to support assemblies of cigarettes and mouthpieces to be united by adjacent rollers, said belts having wire extending along the length of the belt and embodied in the body thereof, and having extended

surfaces for engaging with the grooves of said pulleys to time the travel of the rollers.

9. An endless timing roller belt device for a cigarette machine comprising shafts, rollers rotatably mounted on said shafts, carriers having V-grooves supporting said shafts, clamps oppositely spaced from said carrier, tooth belts having spaced teeth fitted within said grooves and held on said carriers by said clamps, two pairs of sprockets having spaced large and small tooth-shaped grooves for the carriers to fit within the large grooves and teeth of the belts to be driven by the small corresponding grooves to insure that the rollers move in synchrony with the remainder of the machine.

10. An endless timing roller belt device for a cigarette machine comprising shafts, rollers rotatably mounted on said shafts, carriers having V-grooves supporting said shafts, clamps oppositely spaced from said carriers, belts having V-shaped extensions fitted within said grooves and held on said carriers by said clamps, two pairs of sprockets having spaced tooth shaped recesses co-acting with the carriers and belts to insure that the rollers move in synchrony with the remainder of the machine.
